US00D827143S

(12) **United States Design Patent** (10) Patent No.: **US D827,143 S**
(45) Date of Patent: **** Aug. 28, 2018**

(54) **BLIND AID DEVICE**

(71) Applicant: **Toyota Motor Engineering & Manufacturing North America, Inc.**, Erlanger, KY (US)

(72) Inventors: **Rajiv Dayal**, Milpitas, CA (US); **Christopher P. Lee**, Campbell, CA (US); **Douglas A. Moore**, Livermore, CA (US); **Tiffany L. Chen**, San Jose, CA (US); **Patrick K. Ching**, San Jose, CA (US); **Nagisa Adachi**, San Jose, CA (US); **Youenn Colin**, San Francisco, CA (US)

(73) Assignee: **TOYOTA MOTOR ENGINEERING & MANUFACTURING NORTH AMERICA, INC.**, Plano, TX (US)

(**) Term: **15 Years**

(21) Appl. No.: **29/583,588**

(22) Filed: **Nov. 7, 2016**

(51) LOC (11) Cl. **24-01**

(52) U.S. Cl.

USPC **D24/187**

CLAIM

We claim the ornamental design for a blind aid device, as shown and described.

DESCRIPTION

FIG. 1 is a rear perspective view of the blind aid device; FIG. 2 is a front view of the blind aid device of FIG. 1; FIG. 3 is a rear view of the blind aid device of FIG. 1; FIG. 4 is a left side view of the blind aid device of FIG. 1; FIG. 5 is a right side view of the blind aid device of FIG. 1; FIG. 6 is a top view of the blind aid device of FIG. 1; and, FIG. 7 is a bottom view of the blind aid device of FIG. 1.

(Continued)

The broken or dashed lines in the Figures depict portions of the blind aid device that form no part of the claimed design.

1 Claim, 5 Drawing Sheets
